BATTERY TERMINAL CLAMP

Kenneth F. Brown, Burbank, Calif., assignor to
 National Cable & Metal Co., Glendale, Calif., a
 corporation of California

Application July 30, 1937, Serial No. 156,507

2 Claims. (Cl. 173—259)

This invention relates to and has for an object the provision of a battery terminal clamp or connector which is constructed so that it may be securely clamped upon and uniformly engaged and maintained in perfect electrical contact with a battery terminal without being bent, distorted or damaged, or damaging the battery terminal or rendering the clamp difficult of removal and replacement.

Another object is to provide a terminal clamp such as described, which makes for easier and more reliable installations and eliminates the gouging and damaging of the battery terminals, uneven contacts and consequent electrical connection failures, by reason of means located outwardly of the clamping bolt for causing an effective application of the clamping forces without distorting the clamp.

I have shown in the accompanying drawing a preferred form of battery terminal clamp embodying my invention, subject, however, to modification, within the scope of the appended claims, without departing from the spirit of my invention.

Referring to the drawing:

Fig. 1 represents a fragmentary sectional view of the present-day type of clamp, showing the distortion caused by excessive tightening thereof.

Fig. 2 is a fragmentary cross sectional view of the clamp or connector of this invention, as when applied to a battery terminal.

Fig. 3 is a top plan view of the clamp or connector of this invention, as when removed.

Fig. 4 is a longitudinal sectional view of the clamp shown in Fig. 3.

Fig. 5 is a side elevation of the clamp shown in Fig. 3, and

Fig. 6 is a fragmentary perspective view showing the clamp applied to the terminal of a battery.

One embodiment of the battery terminal connector or clamp of this invention, as shown in detail in the accompanying drawing, comprises an apertured, radially split body 7 having an integral socket 8 for a flexible conductor 9, and formed with opposed lugs 10 extended outwardly from opposite sides of the split. The lugs 10 are provided with transverse and aligned bolt receiving openings 11 and with laterally extended abutments 12 on the opposed faces thereof.

These abutments are outwardly spaced from the openings 11 and extend in the direction of one another so that they will engage or meet upon the tightening and clamping of the body 7 around a battery terminal A of a battery B, as particularly shown in Figs. 2 and 6.

It is now seen that the connector or clamp of this invention may be molded, cast, die stamped, or otherwise produced in one-piece form, such that the split body 7 defines two arcuate jaws 7a and 7b, having the lugs 10, or what may be considered as the jaw ends, extended outwardly from the jaws proper, and the abutments 12 extended laterally from opposed faces of said lugs or ends at points spaced outwardly from the bolt receiving openings 11.

The connector is clamped around the battery terminal by means of a bolt 13 which is extended through the openings 11, and has a nut 14 adjustable thereon in the customary manner.

The abutments 12 in being spaced outwardly 15 from the bolt 13, will engage one another and hold apart the other opposed portions of the lugs, as well as the ends of the jaws. This arrangement causes the force or leverage applied by the bolt to contract the body 7 uniformly without causing distortion thereof or of the lugs.

As shown in Fig. 1, when the nut 15 of the conventional clamp 16 is tightened excessively or as is necessary to secure the clamp on the battery terminal 17, the jaws of the clamp, as 25 well as the lugs 18 thereof, and bolt 19 are often bent and distorted. Moreover, the ends of the jaws will bite into and distort the battery terminal, due to the fact that the lugs will bend and force the ends angularly into the terminal. By 30 comparison with my improved clamp shown in Fig. 2, it is seen that tightening of the nut of the latter will cause a uniform clamping action without bending or distorting of the parts of the clamp, due primarily to the peculiar leverage action 35 which results from having the abutment portions 12 arranged to engage one another at points outwardly of the bolt. Should excessive pressure be applied to an extent that might cause the lugs to bend or distort, this would tend to 40 bring the arcuate jaws together arcuately and uniformly as is desired, and without distortion, due to the peculiar application of the clamping forces as aforesaid, and the battery terminal will 45 not be gouged or distorted, as shown in Fig. 1.

While I have shown two abutments 12, it is obvious that one laterally extending and somewhat larger abutment may be employed for the same purpose as said two abutments.

I claim:

1. A battery terminal clamp comprising an apertured, radially split body adapted to be clamped around a battery terminal, aligned lugs of substantially uniform length, extending from said body on opposite sides of said split and pro-

vided with transverse bolt receiving openings, laterally extending aligned abutment portions of substantially uniform length, carried by said lugs at the free ends thereof and adapted to contact one another when said lugs are moved towards one another, and means on said body affording connection thereof with a battery cable.

2. A molded soft metal battery clamp comprising a split body adapted to be clamped around a battery terminal and being capable of deformation when tightly clamped, opposed spaced lugs formed integral with and extending outwardly from said body on opposite sides of the split

thereof and being also capable of deformation when tightly clamped, said lugs having bolt receiving openings, and opposed abutment portions formed integral with and extending from opposed faces of said lugs at points spaced outwardly 5 from said openings and arranged to abut at a point which is on the center line of the clamp and also substantially centrally of the space between said lugs, to prevent unequal deformation of said lugs and said body when said lugs are 10 drawn towards one another for tightly clamping the body on a battery terminal.

KENNETH F. BROWN.
